UNITED STATES PATENT OFFICE.

ALBERT C. FRISCH AND JOHN R. FRISCH, OF WILMINGTON, DELAWARE.

DESIGN FOR A LOUD-SPEAKER HORN FOR RADIO RECEIVING SETS.

Application filed October 19, 1925. Serial No. 15,181. Term of patent 7 years.

To all whom it may concern:

Be it known that we, ALBERT C. FRISCH and JOHN R. FRISCH, citizens of the United States, residing at Wilmington, in the county of New Castle and State of Delaware, have invented a new, original, and ornamental Loud-Speaker Horn for Radio Receiving Sets, of which the following is a specification, reference being had to the accompanying drawing, forming a part thereof.

Figure 1 is a side elevation of the loud speaker horn for radios showing my new design.

Figure 2 is a front elevation of the loud speaker horn for radios.

We claim:

The ornamental design for a loud speaker horn for radio receiving sets as shown.

ALBERT C. FRISCH.
JOHN R. FRISCH.
